C. F. Spencer,
Fruit-Jar.

No 73.846.

Patented Jan 28. 1868.

Attest,

A. V. M. Sprague
R. L. Asgord

C. F. Spencer

United States Patent Office.

CHARLES F. SPENCER, OF ROCHESTER, NEW YORK.

Letters Patent No. 73,846, dated January 28, 1868.

IMPROVEMENT IN FRUIT-JARS.

The Schedule referred to in these Letters Patent and making part of the same.

TO ALL WHOM IT MAY CONCERN:

Be it known that I, CHARLES F. SPENCER, of Rochester, in the county of Monroe, and State of New York, have invented a certain new and useful Improvement in Fruit-Jars; and I do hereby declare that the following is a full and exact description thereof, reference being had to the accompanying drawings, making part of this specification.

Figure 1 is a sectional elevation of my improved jar.

Figure 2, a perspective view of the cover detached.

Like letters of reference indicate corresponding parts in both figures.

My invention consists in the combination of hinged loops of the cover, with notched lugs or projections of the jar-neck, whereby the cover may be fitted and held accurately on the packing-ring, whether cut thick or thin, and whether the seat for said packing-ring is ground accurately or not.

In the accompanying drawings, A indicates the jar, and B the cover. The jar has nothing peculiar in its construction, except that on two opposite sides the neck has lugs or projections, *g*, blown outward, these lugs or projections being provided with series of notches, *b b*, one above another, as shown. The top of the jar is also ground off square to receive the packing-ring *c*, of rubber. The cover is made of a single piece of sheet metal, "struck up," so as to form a projecting flange, *d*, which rests upon the packing-ring *c*, and presses into it to seal the jar. On opposite sides, loops *f f* are hinged to the cover so as to turn up or down; and when the cover is in place on the jar, these loops catch and hold in the notches *b* of lugs *g*.

The great advantages arising from this arrangement consist in the facility with which the cover can be applied or removed, and the readiness with which it adapts itself to packing-rings of different thicknesses, and any inclination of the seats on which the packing-rings rest. Packing-rings of this kind are cut from rubber tubing, and are liable to be of different thicknesses. In ordinary jars much difficulty is experienced from this source, for the reason that the covers cannot be adapted to these differences. In jars of this kind, also, where the top of the neck is ground off to form a seat for the packing-ring, it is found impossible to grind them all square; many of them are more or less inclined. Ordinary covers cannot be made to fit these inclined seats, and for this reason many jars are found useless. These two great difficulties are entirely obviated by my improvement. The notches *b* allow the loops *f* to be fitted higher or lower to adapt to the thickness of the packing-ring, or to incline to one side to fit any incline in the seat at the top of the jar for the packing-ring.

In addition to these advantages the construction is very simple, and the arrangement is cheap, much more so than in those jars where tightening-clamps or screws are employed. The loops, in addition to the purpose of attaching to the jar to hold the cover down, serve, when turned up, as an attachment for a lever, *h*, for removing the cover from place against the atmospheric pressure.

What I claim as my invention, and desire to secure by Letters Patent, is—

The combination of the hinged loops *f* of cover B with the notched lugs *g* of jar A, for the purpose of adapting to different thicknesses of the packing-rings, and to different inclinations of their seats, the whole arranged as described, and operating in the manner and for the purpose set forth.

In witness whereof, I have hereunto signed my name in the presence of two subscribing witnesses.

Witnesses:

W. M. W. NETTERFIELD,
R. E. OSGOOD.

CHAS. F. SPENCER.
